AUTOMATIC CUSHION STUFFER WITH
BELT CONVEYER AND RECIPROCAT-
ING FOLLOWEREdward J. Stauffer, Naperville, Ill., assignor to
Kroehler Mfg. Co., Naperville, Ill., a corpora-
tion of Illinois

Application November 29, 1946, Serial No. 712,859

4 Claims. (Cl. 226—45)

1

The present invention relates to apparatus for manufacturing upholstery cushions or the like and is concerned more particularly with a stuffing machine in which the cushion filler charge is advanced on a conveyor belt from a loading position until ultimately it is discharged into a cushion covering material preparatory to sealing and completion.

In its specific contemplation as herein disclosed the present invention is applied to a cushion stuffing apparatus in which the cushion filler is made up of a spring assembly enveloped with fibrous padding. The cushion covering is made of a substantial ornate and serviceable fabric of which all of the defining panels but one are previously positioned and sewn together. The stuffing charge is advanced on a conveyor system until it arrives in a position in transverse alignment with the distended cushion covering. Thereafter, electrically supervised timing apparatus functions to operate a compression mechanism which thereupon constricts the filler charge so that it may be inserted into the liner or covering material, the latter member being held on the outermost end of a metallic chute or sleeve.

The filler charge after being compressed passes through the chute and is positioned within the liner by a transversely operating plunger. Further movement of the plunger discharges the filler load and cushion liner together, after which the cushion is completed by sewing into place the remaining open panel.

For a more comprehensive understanding of the present invention, reference will now be had to the accompanying drawings and to the following detailed specification and in which like reference characters designate corresponding parts throughout and in which:

Fig. 1 is a plan view of a cushion stuffing apparatus and filler charge conveyor with a portion of the discharge chute broken away.

Fig. 2 is a front elevation of the apparatus featured in Fig. 1.

Fig. 3 is an end elevation of the same apparatus viewed as indicated by the line 3—3 in Fig. 1.

Fig. 4 is an enlarged rear elevation of the compression framework and the related end of the conveyor apparatus.

Fig. 5 is an enlarged detail view of a reversing switch mechanism for controlling the direction of rotation of the press operating motor.

Fig. 6 is a transverse sectional view through the plunger operating mechanism and its gear reversing train.

2

Fig. 7 is a perspective view of a portion of the conveyor belt showing an adjustable wall bracket mounted thereon; and

Fig. 8 is a sectional detail view of a safety catch lever and is taken approximately on line 8—8 of Fig. 4 showing the lever in full as well as in dotted positions.

Referring now more particularly to the illustrations in the accompanying drawings, attention is directed in Figs. 1 and 2 to the endless conveyor belt generally designated 11 with its articulated link elements comprising two spaced chain components which are adapted to mesh with the idler sprockets 12 at one end of the conveyor system and with the driving sprockets 13 at the other end. The driving sprockets 13 rotate clockwise as viewed in Fig. 2, being powered through their driving shaft 14 (see also Fig. 4) by means of a link belt 15 which meshes with the driven sprocket wheel 16 as well as with the driving sprocket 17 carried by a speed reduced shaft 18 of a gear reduction apparatus 19. An idler sprocket 21 takes up the slack in the link belt 15. The gear reduction apparatus 19 is driven by a motor 22 which rests in the base structure 23, Figs. 2 and 4, and in addition to driving the gear train 19, motor 22 also drives through a gear reduction system carried in the unit 23, a cycling or timing platform 24 which carries one or more impulsing cam projections 25 for a purpose which will be further described hereinafter.

Attention is again directed to the link belt 15 which drives the conveyor shaft 14, Fig. 1. It is to be noted that alongside the driven gear 16 is a clutch hub 26 in which are provided conventional elements of a driving coupling supervised or controlled by means of a bell crank 28 pivoted at 29 and periodically actuated as will later be explained for the purpose of advancing the conveyor belt from one position of alignment to another intermittently, a condition of alignment being such as that illustrated in Fig. 4, whereat a filler charge disposed between the confining walls 31 and 32 is positioned beneath the compression head 33, carried by the screw actuated plunger 34.

At the end of the conveyor featured in Fig. 4 there is provided a supporting tower structure generally designated 35 made of vertical angle members 36, a top cross member 37, motor supporting platform 23' and the intermediate reinforcing straps 38. The compression head 33 is carried at the end of a plunger casting 41 reinforced by the truss straps 42 on the lower extremity of the plunger shaft 34, the upper end of which

is screw threaded as best seen in Figs. 2, 3 and 4. The lower portion of the shaft 34 is splined as at 43 and by means of a key carried in the supporting structure at 44 the shaft 34 is confined against rotation being instead limited to vertical motion when the threaded driving nut 45, Fig. 4, is actuated by the reversible driving motor 46.

Shaft 34 after passing through the threaded driving nut 45 is guided as at 47 so as to align the compression head 33 with the space between the two confining walls 31 and 32. The depth of stroke, which is described by the compression head 33, is regulated by means of a pair of limit switches 48 and 49 which are adjustably mounted upon the structural elements 51. Each switch is provided with a spring urged follower roller 52 or 53, the former of which rides on one side of shaft 34 into and out of the recess 54 while the other similarly does so with respect to the recess 55. More about the electrical control with reference to these limit switches will be indicated in the description of operation following hereinafter.

Calling attention now more specifically to Fig. 7, the conveyor system theretofore is represented by a pair of endless link belts designated 53 and 59. These belts are held in alignment because their respective driving and idler sprockets 13 and 12, there being two on each shaft, are integrated for this purpose. The conveyor is provided with a series of cross bars 61 as best shown in Figs. 1, 2 and 7, each secured to a related pair of opposed links on the belts 53 and 59 and each provided at one end with latching plates 62 extending above the surface of the bars 61 and having the latch receiving openings 63. At the opposite end each cross bar 61 is correspondingly provided with a narrow end plate 64, similarly provided with openings 65. Into one or the other of the openings 65 of each plate 64 there may be inserted the bayonet projection 66 of an immovable rod welded to the sheet metal floor piece 67, which comprises one or the other of the wall members 31 or 32. The upright panel 68 of said wall member merges into an angling flange 69, and the assembly is held rigid having welded between the flange 69 and the floor piece 67, a pair of endwardly disposed brace rods 71.

In opposition to and in linear alignment with each rigid bayonet rod 66, there is provided a slidably latching rod 72 which resembles a conventional barrel bolt and which may be manipulated by the handle 73. After the rod 66 has been inserted into an opening 65 of a plate 64 and the rod 72 is inserted into an opening 63 of an opposite plate 62, an end wall element 31 or 32 is thereby effectively anchored to the conveyor system so as to swing freely around the end sprockets, as best indicated in Fig. 2 and in all respects to move as a portion of the conveyor system, generally designated 11.

At the end of the apparatus remote from the superstructure 35, a loading operator fills the space between the conveyor wall elements 31 and 32 with the cushioning material or batting which may include an integrated upholstery spring assembly covered by suitable fibrous packing or batting and the charges thus placed advance by intermittent steps rightwardly, as viewed in Figs. 1 and 2 (leftwardly as viewed in Fig. 4) until each charge reaches the compression position or station which for convenience will also be designated as the alignment position, beneath the compression head 33.

Just before this position is attained by each

successive charge, an engaging pin 81 carried at one end of each of the wall members 32, see Figs. 4 and 7, encounters a pivoted hook 82 articulated at 83 to a bar 84, rotating the latter member throughout a small angle counterclockwise about its pivot 85. As a result of this operation, the bar 86, which is pivoted at 81, is thrust leftwardly, Fig. 4, distending the return spring 88 which is connected between an integral projection 89 of bar 86 and the guide bracket 91, causing the adjustable actuating screw 92, Fig. 1, to engage the bell crank 28 and rock the latter clockwise about its pivot 29. This effects a de-clutching operation, whereby the driving connection between the chain 15 and the conveyor 11 is momentarily broken.

As a further result of the aforescribed counterclockwise movement on the part of control lever 84, a camming pin 93 carried thereby and riding within the slot 94 of a bell crank lever 95, Fig. 4, causes said bell crank lever to be rotated counterclockwise about its pivot 96 so that the opposite end of said bell crank lever 95, carrying a pin 97, which at this time engages beneath the shoulder 98, raises the slidable control rod or bar 99 from its position as indicated in Fig. 4 to one sufficiently higher therefrom to effect a reversal of the relative disposition of the switch arms 101 and 102, Fig. 5, of the reversing switches 103 and 104. As a consequence electric current introduced to the winding of motor 43 is in such direction as to cause the driving nut 45 to lower the threaded plunger shaft 34, which operation will continue until the shoulder 105 encounters the limit switch lever 53, at which time the current will be arrested momentarily while the discharging operation takes place.

Carried on the plunger 33 is a camming finger 80, Figs. 4 and 8, which as the head reaches its lowermost extremity of travel, engages the tail end 90 of a safety lever pivotally supported on an inert part of the machine, and having a blocking finger 100 that is placed into the path of rocker bar 84 so as to prevent the latter from rotating clockwise about its pivot 85 sufficiently to cause the inadvertent reengagement of the driving clutch 27. This safeguard is provided in order to assure that the conveyor apparatus is not reinstated into motion while the compression head 33 is in its down position, but instead to delay the restarting of the conveyor until after the head 33 has cleared the level of the confining walls 31 and 32.

When the cushion compressing head 33 reaches its lowermost limit of travel as may be adjustably predetermined by placement of the limit switches, the projection 107, Fig. 3, which is carried on the extremity of the beam 108 strikes the head 109 of a bar 111, see also Fig. 6, which is supported on the guide brackets 112 and depresses said bar 111 against the tendency of return spring 113 until a pin 114 carried by said bar strikes the inclined surface of a cam projection 115 integral with an arm 116.

As a result of the previously described engagement, cam 115 is moved leftwardly as viewed in Fig. 6, carrying with it the arm 116 which is articulated at 117 to a shifting lever 118, whereupon the latter rotates clockwise about its stationary pivot 119 causing its idler pinion 133 to come into meshing engagement with the rack bar 122.

Attention will now be momentarily directed to a driving motor 123 which is continually oper-

ated and whose driving pinion 124 meshes with the links of a chain belt 125, imparting counterclockwise rotation to the driven gear 126. A driving gear 127 which is fast to the shaft 128 that also carries the aforesaid driven gear 126 thereupon extends the counterclockwise rotation through its link belt 129 to a driven gear 131, which is integrally associated with a driving gear 132. Said gears 131 and 132 rotate freely on shaft 119 and gear 132 meshes with a pinion 121 which in turn meshes with a companion pinion 133. Consequently, pinion 121 undergoes clockwise rotation as viewed in Fig. 6 while pinion 133 rotates continuously in a counterclockwise direction.

When, therefore, the rocking lever 118 is thrust clockwise effecting meshing engagement between pinion 133 and bar 122, the latter member being part of the thrust ejector 134 moves to the left (see Fig. 3), until the ejector head 135 discharges the compressed cushion package out from beneath the piston head 33 into the rectangular enveloping sleeves 136 and 137, Fig. 2, on the outside of which the operator has previously placed the partially sewn cushion cover. In fact the thrust imparted by the plunger 134 extends far enough so that the cushion package engages the sewn cushion cover causing the latter to be withdrawn from said enveloping sleeves at which time the cushion stuffing operation is completed.

Plunger 134 which is indicated cross-sectionally in Fig. 4 carries an arm 110 which supports a tripping finger 120. During the leftward movement of plunger 134 as viewed in Fig. 6, finger 120 engages the camming surface 130 of a release bar 140 moving it leftwardly against the influence of its spring 150. However, on the return movement of plunger 134 rightwardly, Fig. 6, this finger engaging the opposite surface of camming projection 130 forces bar 140 rightwardly and to strike the control rod 99 shifting the latter to the right, Fig. 4. As a result, the shoulder 98 is dislodged from the pin 97 and the bar 99 is permitted to descend in response to gravity aided by its return spring 148.

When the stuffing operation is finished the cushion cover is closed by sewing its remaining open flap into position thereby completely encasing the cushion filling. As the plunger 134 and its continuation 122 reach the extremity of travel, a pin 138 on the tail end of the rack bar 122 engages the control lever 139 which is pivoted at 141 and articulated through a link 142 with the lever 118. As a result the lever 118 is rocked in a counterclockwise direction about its pivot 119, whereupon pinion 133 is withdrawn from engagement with rack 122 and pinion 121 is shifted to so engage in its stead. As a result of the striking of pin 138 against the upper end of lever 139 the latter is rotated counterclockwise and through link 142 lever 118 is also rotated counterclockwise withdrawing driving pinion 133 from engagement with rack bar 122 and since this movement partakes of sufficient momentum the overcentering spring 143 carries the movement beyond dead center causing the pinion 121 to engage the teeth of rack bar 122. The clockwise rotation of pinion 121 withdraws the plunger 134 to the condition in which it is illustrated in Fig. 6 at which time another pin 144 carried at the side of rack bar 122 engages the upper extremity of lever 139. In this case, however, the pin 144 is so critically located that its thrust is sufficient only to reinstate the assembly into a neutral position. That is to say, its striking

5 against the lever 139 and rocking it in a clockwise direction is a critically milder thrust so that the motion transmitted through link 142 to lever 118 withdraws the pinion 121 from meshing engagement with rack bar 122, but does not thrust pinion 133 into engagement therewith. Accordingly the apparatus is restored into the condition which is illustrated in Fig. 6.

10 The aforescribed ejector operation which is performed by the mechanism illustrated in Fig. 6 requires a predetermined interval to consummate. After plunger 134 has completed its cushion discharging operation, the compressing apparatus is restored to its original position with the head 33 fully raised, and this result is supervised by a timing disc 24 which carries on its surface a number of cams 25 already mentioned above. The operation cycle is so regulated that a cam 25 among several such cams that may be 15 carried by disc 24 encounters the follower wheel 145 at the end of the trip bar 146. The latter member is confined for vertical motion in a pair of brackets 147 and when raised, this member engages the hook lever 82 which is pivoted at 83 lifting it clear of the pin 81. This frees lever 84 which is under influence to rotate clockwise about its pivot 85 by virtue of the clockwise torque of bell crank 95 communicated to the latter member by the reversing bar 99 whose shoulder 98 has been resting on the bell crank pin 97. This force is not only gravitational, but is supplemented by the spring 148. As a consequence bar 99 drops down sufficiently to reverse the switches 103 and 104 whereupon the motor 46 20 begins to operate in a direction for lifting the screw 34.

25 As a further result of the clockwise motion of lever arm 84 which pulls at its articulation pivot 87 the clutch control bar 86 is moved rightwardly, Fig. 4, reengaging clutch 27 and causing the rotary motion of continuously rotating gear wheel 16 to be imparted to the conveyor system. Meanwhile, the attendant at the far end of the conveyor has placed another cushion stuffing assembly into a space between another 30 pair of brackets 31 and 32, first appearing on the upper surface of the conveyor. Between such loading operations this attendant may be occupied in preparing the coil spring assembly by enveloping it with felt padding. When the cam 25 35 has overridden the roller 145, bar 146 drops back to its lowermost position and the hook lever 82 is freed so as to be engaged by an oncoming pin 81 of the next supporting bracket 32.

40 55 Thus, there is described a complete cycle of operation on the part of the automatic mechanism. It is to be observed additionally that but two attendants are required to supplement the work performed by the described machine, one of whom supplies the conveyor with cushion loads or charges and the other of whom applies the cushion cover and stands ready to receive the filled cushion and cover at the time the plunger 134 makes its cycle of operation.

60 65 In order to replace a succeeding cushion cover upon the overlapping sleeve elements 136 and 137, the latter members are mechanically compressible one within the other under the control of a foot pedal 151, Fig. 2, which is pivoted at 152 and to which is connected at 153 a spring loaded link 154 at whose upper extremity there are pivotally articulated as at 155 the spreader arms 156 and 157. The effect of depressing pedal 151 is to pull link 154 downwardly to draw the link arms 156 and 157 inwardly, and thereby to shift the

lever arm 158 leftwardly so that its yoked extremity 159 engaging collar 161 moves the latter toward the left and with it the threaded shaft 162. This shaft is screw threaded as at 163 and may thereat be adjusted with respect to a bracket 164 carried by element 136. A spring (not shown) maintains the sleeve assembly 136—137 distended until overpowered by the aforescribed foot pedal mechanism.

This foot control makes it possible to apply a cushion cover easily and more conveniently and without having to pull it over these elements under spring tension.

While the present invention has been explained and described with reference to a more or less specific embodiment, it is to be understood, nevertheless, that a reasonable realm of modification and variation may be incorporated without departing from the essential spirit or scope thereof.

The invention claimed is:

1. In a cushion stuffing machine, a conveyor mechanism for advancing a plurality of cushion stuffing charges from a charging station to a compressing station intermittently, a compressing apparatus at said compressing station for constricting cushion stuffing charges carried by said conveyor mechanism, an expansive sleeve for holding a cushion covering material in alignment with the compressing apparatus, a plunger for discharging the compressed material into said cushion covering including a cyclically operable power train apparatus, an automatic tripping mechanism having a normally poised position from which it is initiated by said compressing apparatus for releasing said plunger, and a timing cam for reinstating said tripping mechanism to its poised position.

2. In an automatic machine for manufacturing upholstered cushions, a conveyor having a plurality of sets of filler material confining partitions, each adjustable on said conveyor in accordance with predetermined dimensions, a power operated train for actuating said conveyor throughout intermittent steps of advancement corresponding to distances between consecutive sets of said filler partitions, a clutch between said train and said conveyor, means responsive to the arrival of each set of filler partitions before a compression position for declutching the power train from the said conveyor, a pair of reversing switches, said means including a control lever movable to also supervise said pair of reversing switches, a compression head including an electric motor capable of reversible rotation under the supervision of said pair of reversing switches,

55

electric circuit connections between an energizing source and said reversible motor under the supervision of said switches for moving said compression head downwardly to a predetermined adjustable level, a cushion discharging plunger, a power driven train for thrusting said plunger outwardly and for retracting said plunger, and means controlled by said plunger for reinstating said reversing switches and for reclutching said conveyor and said conveyor driving train.

3. In an automatic cushion stuffing apparatus, a power source, a conveyor apparatus for advancing filler loads to a compression station, a clutch for connecting said power to said conveyor apparatus, a motor driven compression mechanism at said compression station for compacting said filler loads, a discharging plunger for ejecting said filler loads, and automatic means responsive to each attainment by said conveyor of said compression station for declutching said power source from said conveyor, for initiating the compression plunger, and for operating said plunger.

4. In an automatic machine for filling furniture cushions comprising a conveyor having a plurality of confining partitions, a power operated train for advancing said conveyor intermittently, means responsive to each intermittent advancement of said conveyor for declutching said train from said conveyor, a pair of motor reversing switch devices, a compression head including an electric operating motor wound for reversible rotation under the alternative supervision of said pair of switch devices, electric circuit connections between an energizing source and said motor under the supervision of said switch devices for moving said compression head downwardly and upwardly in separate operations, a cushion discharging plunger including a power driven train for projecting and retracting said plunger, and means controlled by said plunger for operating said reversing switch devices.

EDWARD J. STAUFFER.
